United States Patent Office

Des. 212,624
Patented Nov. 5, 1968

212,624

COMBINED CABINET AND WORK BENCH

Royce F. Evans, 1625 Highway 30 West,
New Haven, Ind. 46774

Filed July 21, 1967, Ser. No. 7,933

Term of patent 14 years

(Cl. D33—19)

FIG. 1

FIG. 2

FIG. 3

FIG. 4

FIG. 5

FIG. 1 is a front perspective view of a work bench and combined cabinet showing my new design;

FIG. 2 is a rear view thereof;

FIG. 3 is a front view thereof;

FIG. 4 is a side view thereof (the other side having the same appearance); and

FIG. 5 is a top plan view thereof.

I claim:

The ornamental design for a combined cabinet and work bench, shown and described.
